(54) LAMPS

(76) Inventor: **Alexander Black**

Alexander Mackie
Sellers Patent

This schedule referred to in the Sellers Patent and marking part of
the same containing a description on the words of the said Alex
Mackie of his improvement in Lamps.

The Lamp is a common Argand Lamp for light houses and
the wick is raised by a screw the same method of heating to be
applied to any other kind of Lamp. After heating the oil a pipe,
cyphon, tube hood inverted funnel or cap of glass or other met-
al, square round, or any other figure that the heated air may
be driven into around over or under the oil. One end of the hood
or other consequence is attached to the base of the vessel with
a hole for the smoke such as to enter, and the base placed and
lashed to the fountain closely so that no smoke passes out in
between the two edges of the base and fountain set closely. Two
small holes near the union with the fountain for discharging
the smoke which collects between them. When large reflectors are
used a hole is cut through the reflector, so placing the glass upon
the lamp. Directly over this hole inside of the reflector a rod
of wood or any is applied to carry the smoke through behind the
reflector which is applied on the pipe cyphon tube hood in-
verted funnel or cap in the same manner as will small reflector
After a solid rod or bar of metal will produce a semipine effect
for the lamp pipe by inserting a metal rod through the foun-
tain of the lamp with its top bent over the flange of the
lamp and made hollow before the hood or cap before marking
so that the blaze may operate on the inside of the cavity and
heat the metal. At the bottom of the rod which extends through
the fountain a large metal hollow may be soldered to return the
heat between the base and fountain. The hood or cap part
of the rod may be one half of an inch more or less in the thick-
ness, and the rod may be made one half inch longer or less

and either square, round or any other shape. The end of a rod may be applied without heat to a rod or pipe over the blaze, the rod may be of copper or any other metal, ^{which} will conduct heat and is equally applicable to all lamps to which it may be applied by inserting in a ^{dark} place inside the lamp to turn it ^{right} side up the blaze. One convenience of the rod is, that it, ^{itself} may be placed over the blaze in winter and turned from the blaze to the back of the lamp in summer. Around the outside case of the furnace is a woolen waffler, or, a number of stuffing of wool, cotton or some warm covering quilted and fastened to a leather, and is made into a pocket to retain the heat if necessary. A pocket is also attached to the bottom of the tube of Argand lamp to draw off the oil by day that it may not chill and prevent its burning by night.

The saving the wicks. A sheave or band wheel is placed around the hoop and the hoop when turned ^{over} ^{over} the stock of a tube, which holds the wicks.

The stuffing the lamp. A perpendicular wire passes through the center of the inside tube of the Argand Lamp, with a right-angled fitting which connects over the wicks and breaks off the brush. This wire is provided in a central position by a hole there a small cross bar near the top of the inside tube and by a socket at the bottom of the crooked bar, mounting on the upright post having a notch through which it is passed against the outside of the lamp, to adjust the height of the finger for stuffing and the finger may be applied, like the hand of a clock ^{but} to the a stuffing bottle. A sheave or band wheel is fastened at the bottom of this wire, by which it receives its rotation. The vertical band wheel which turns the hoop for raising the wicks may be the winding diameter and may also go by stockman's. And the wheel or band wheel which moves the finger to brush off the wicks or brush may be made of diameter and moved by the same method as the band wheel.

for raising the weights. The motion to these wheels is given by the bands, which pass round the weights or wheels, and then pass over the pulleys at the edge of the table, and have balance weights at their ends to hold them.

The other end of these bands, are fastened to two wires, which descend to the lower part of the light house; and these two wires are fastened to slides on the iron of a lever graduated like a Dumb-bell in balance; that they may be moved further towards the center to increase the motion, or nearer to the fulcrum to lessen it.

The lever may be four or five feet in length, or less, the weight being suspended near one end and the wires attached to the slides, between that and the junction or centre of motion.

Other forms of wires may be applied. The weight is a buoyant vessel, floating floating in a liquid contained in another vessel, which has a cock, or aperture through which the liquid may be run. The best shape of these vessels, is a framework of an inverted cone. The one which contains the liquid, should have a strainer to prevent any obstruction from entering the cock, and the buoyant vessel must be adjusted by weights sufficient to procure its gradual descent. Wheels, and wires, may be applied for the same purpose.

In order to carry off the smoke and vapor of the lamps, from the lantern, a large inverted funnel may be suspended over the whole, with its pipe rising through the centre of the lantern. Upon the tunnel's place reflection, made to curve over the lamps, so that the blaze from the lamps, will run up them, and have the appearance of double lamps. These reflectors are stationary, and when the lamps are turned they are still placed there for the purpose, and when turned replaced. The method of these improvements of Argand's lamps, for light houses is as follows. Place the lamps on the table and set them firmly. Pass a band around the aching or wheels, for raising up or raising the work, and over the pulleys, at the edge of the table,

attach one end of the barrel to the wires, which extend from the bottom of the light house. To the other end of the barrel let a weight sufficiently heavy to extend the vessel, pass another barrel in a similar manner around the vessel, or wheel of the ship, passing and fasten one end to a wire and the other to a weight as before described. Attach the barrel ends to the two wires to the sides of the vessel, and applying the buoyant weight to the end of the wire. This will turn the vessel like the percolation of the water through the rock becoming nearly a stream. Turn the boat so that the descent of the buoyant weight moves the vessel or wheel of the ship, and a rudder and by reversing the sides on the boat, adjust them reversely, should the motion of the boat not continue a sufficient length of time either diminish the stream of the liquid or remove the sides of the boat more to buoyant weight. The rock is a article for starting her, a natural stone suitable for the ship or barrel to quay with exact size of the hole for heating. The liquid adapts into a tub from which it may be pumped, or dipped into its original container. The following directions may be considered as requisite for calculating the machinery for the foregoing purpose. The vase for containing the liquid may hold 150 gallons, more or less. The buoyant weight may be large enough to hold 25 or 30 gallons and to be about one half loaded with weight. The liquid used for the aforesaid purposes, must be of such a nature as not to be rendered inebriating frost such as, ardent spirits, picric, or the bitter water of salt wells. I have also made the following improvement in the management of the light house: while wash the glass on the land side and give a proper inclination to the reflectors, in order to throw the light higher and cast a better light on the ocean. I have also invented a lamp for warming the hands and feet of seamen whilst steering a vessel. It has a wide article made of pipe or from three or four inches in diameter until at the lower end when placed in an aperture to be made in the

deck of a vessel for receiving it. I then make another tube or pipe of copper, or any other metal, that will retain and conduct heat, 11/2 from four to five feet in length, and of about 3 inches in diameter; this tube or pipe is flattened so as to have an aperture from one eighth to one fourth of an inch and is made just to the size of a vessel having the immutability of copper and an aperture made in the deck. The small or narrowest end of the first mentioned tube or pipe, is then inserted in this aperture, and fastened or connected to the bottom or lower side of the flattened tube or pipe fastened on the deck. The lamp is suspended over the cabin, immutably and directly under the first mentioned tube or pipe, and is so fast by wires attached to the lamp, over the blaze and to the deck; and kept in that position, so that the flame or blaze of the lamp will strike directly to the centre of the mouth or open end of this tube, or pipe, so that the heat may be conducted to the flattened tube or pipe fastened on the deck of the vessel, and upon a metal plate or button, about one or two inches thick and three or four inches diameter. To this plate or button is affixed or secured in a way which will receive the heat from the lower tube or pipe, to which the man at the helm or steers his hands when cold. His feet also may be warmed by stepping on or applying them to the flattened tube or pipe fastened to the deck. The ends of this tube are left open for discharging the smoke. Holes placed between the deck and flattened tube or pipe will prevent it from burning the deck. The same principle can be applied to any house or dwelling and carriages of any kind. I also make a lamp for warming the feet and giving light to a person travelling on horseback or in a carriage in cold, dark weather. To do this I make a case or slipper of copper sufficiently large to contain the feet.

and admit a small lamp in front of it with glass. This slipper which is made to fit, when put on, will cover a great part of the foot, and the heat from the blaze of the lamp striking against the copper will communicate warmth to the foot whilst the light is reflected on the road. I also make a gas light lamp which furnishes itself with gas. I take a common Argand's lamp or any other lamp, a candle or fire place ^{in a} and over the pan-pot. Set the blaze of the lamp or fire which after a vessel nearly half filled with pitch, tar or resin. From this vessel a tube may lead to my part of the house from whence a light will proceed when set fire to. This blaze may also strike against another vessel half filled in the same manner with pitch, tar and a pipe leading from it will convey the light and so on to any number of lights. I have also erected a model of a striking bell to be placed on dangerous ledges and shoals for the preservation of lives of seamen and property.
